FIG. 5

Patented Dec. 12, 1922.

1,438,756

UNITED STATES PATENT OFFICE.

GERALD FRINK, OF SEATTLE, WASHINGTON.

CABLEWAY.

Application filed April 21, 1921. Serial No. 463,429.

To all whom it may concern:

Be it known that I, GERALD FRINK, a citizen of the United States of America, and resident of the city of Seattle, in the county 5 of King and State of Washington, have invented certain new and useful Improvements in Cableways, of which the following is a specification.

My invention relates to cableways and 10 particularly to a type of cableway which is particularly designed for use in logging.

The object of my invention is to provide means whereby cableways of this character may be conveniently and quickly shifted in 15 position, as is required by the nature of the work, so that the cableway may be moved as may be required for the progressive logging of a considerable area.

The object of the invention, more specifically stated, is to provide means whereby the 20 outer or tail end of the cableway may be laterally shifted for operation over a new strip of ground.

The construction and operation of a device 25 embodying my invention will be hereinafter described and the particular features thereof which I believe to be new and upon which I desire to secure Letters Patent will then be particularly defined by the claims.

30 In the accompanying drawings I have illustrated a type of construction for carrying out the purposes of my invention which is of the design now preferred by me.

Figure 1 is a diagram showing a cableway 35 of the type with which my invention is intended to be employed, the same showing the location of my improved constructions.

Figure 2 is a diagram showing in plan the manner of applying my invention to shift 40 the tail end of the cableway laterally to a new location.

Figure 3 shows in elevation on a larger scale, the manner of applying my invention.

Figure 4 is a diagram showing in plan the 45 particular type of engine which would preferably be employed in operating a cableway of this character.

Figure 5 is a diagram showing in plan a modified manner of operating my invention 50 in shifting the cableway.

It is one of the purposes of my invention to provide means whereby the power of the cableway and its operating engine may be employed for the shifting of the tail end of 55 the cableway to a new location laterally removed from the former. The type of cable-

way for which my invention is peculiarly adapted is that type which employs a looped main line, that is a main or trackway line which has its two ends secured at the head 60 end, each to its respective drum of the engine, the cableway extending as two sections or runs to the outer end, at which point it passes about a sheave or block. In such a cableway the main or trackway line is capable of being operated so as to let out one side and haul in the other or to let out or haul in both sides at the same time, as may be desired or necessary.

In the particular cableway shown in the 70 drawings such a looped or double main line is employed consisting of the two sections 1 and 10, the outer or looped end of which passes about a tail block 2. The inner ends of this line extend to and are secured each to 75 its respective one of the drums 3 and 30. These are the drums which, in the type of engine illustrated are located nearest to the boiler. These drums are designed to be operated by their engine, either both together 80 or one at a time, as may be desired. Upon the cableway is a carriage 15 which is caused to travel thereon by the means of a hauling line 16 and a back haul line 17. The latter is returned to the engine through any convenient 85 route, being guided by sheaves or blocks at such points where this may be needed.

In a cableway built in accordance with my invention, the main line tail block 2 is not secured or coupled close to the tail tree 4, 90 but is supported by a cable, as 40, of some little length. The connection of the cable 40 with the tail block 2 is through the medium of a member, as 5, which serves a double purpose, first to steady this line in 95 such manner as to prevent rotating of the block as a whole about an axis extending in the direction of the cableway, and second to provide means for conveniently attaching thereto the shifting line by which the tail 100 end of the cableway is shifted from one location to another.

This member, as shown more particularly in Figure 3, is in the form of a triangular plate provided with means at each of the 105 corners for attaching a line thereto and also provided with means for making attachment thereto at points intermediate of the corners. The tail block 2 is secured by a shackle or any other suitable means to one corner of the 110 triangle and the supporting line 40 to another corner.

Secured to the third corner is the steady-
ing line 50 which is placed so as to extend
laterally from the direction of the cableway
and line 40. Sufficient tension is placed
upon the line 50 to resist any tendency
of the plate 5 and the tail block connected
therewith turning about the axis of the
cableway. It is important, in operating a
cableway of this sort that the block 2 be
held so as to extend in a vertical plane, as
otherwise the lines might become twisted
and the operation of the carriage thereon be
prevented. By providing a member as the
plate 5, which is secured in or to the suspend-
ing support, for the tail block 2 as the line
40, and securing thereto a steadyng line, as
50, turning of the block about the axis of
the cableway will be prevented.

When it is desired to shift the tail end of
20 the cableway, a block as 7, is secured in ele-
vated position to the new tail tree 70.
Through this is run the shifting line 71.
One end of this line is secured to one of the
sides 1 or 10 of the main line of the cable-
way. This may be done by any convenient
25 means. In the drawings I have shown a
clamp 72 which is adapted to be secured to
the cableway line and to have the shifting
line 71 secured thereto.
30 The other end of the shifting line 71 is
secured to the tail block of the cableway.
While this might be directly secured to the
tail block it is more convenient to secure it
to the tail block indirectly, or through the
35 medium of the plate 5. I have therefore
shown this end of the shifting line as being
secured by a shackle to one of the interme-
diate holes in the plate 5.

In the plan of operation illustrated in
40 Figures 2 and 3, this shifting line passes, be-
tween the block 7 and the tail block of the
cableway, through a second block, as 73,
which has secured thereto a snubbing line 8.
This snubbing line is passed about either the
45 tail tree or a stump or a tree adjacent to the
old location. In making the shift, the main
cableway line is operated so as to haul in
upon the shifting line which has been se-
cured thereto. The first effect of this will
50 be to slacken the strain upon the line 40
by which the cableway has heretofore been
connected with and supported from the tail
tree 4. The cableway may thus be conven-
iently disconnected from the tail tree. When
55 this has been done, further hauling in of the
shift line 71, through the operation of the
main line 1 and at the same time suitably
letting out or slackening off upon the snub-
bing line 8, will cause the end of the cable-
60 way to be shifted across from the old loca-
tion to the new, at which place the tail block
2 may, through manipulation of the shifting
line 71, be drawn towards the tail tree as
necessary or desired, and the normal sup-
65 porting tackle, consisting of the line similar

to the line 40 and the steadyng line 50 may
be attached thereto.

In this shifting operation, sufficient strain
is maintained upon the cableway to support
it in the air, so that in shifting across, the
cableway need not engage with any objects
on the ground. The blocks and lines em-
ployed in shifting the cableway and in se-
curing it at the new location may be put in
place while the cableway is in operation at
the old location. It is a matter of but a few
minutes to make the necessary connections
and to shift the cableway to the new loca-
tion. This has been done in as short a time
as fifteen minutes and this for a cableway
of very long span, approximately one mile
span. It is thus seen that this particular
mechanism contributes very materially to
maintaining the cableway in condition for
uninterrupted operation.

In Figure 5 a slight modification is shown.
In this case the snubbing line 8 is not pro-
vided with a sheave or block through which
the shifting line 71 passes, but is connected
directly to the tail block or to the plate 5
which would be the equivalent thereof.
Other than this the operation of the device
as shown in Figure 5 would be as previously
described.

What I claim as my invention is:

1. A means for laterally shifting a cable-
way having a looped main line and a tail
block for said line, comprising a block se-
cured at the new location, a shifting line
passing through said latter block and hav-
ing one end secured to one side of the main
line and its other end to the tail block. 95

2. A means for laterally shifting a cable-
way having a looped main line and a tail
block for said line, comprising a block se-
cured at the new location, a shifting line
passing through said latter block and hav-
ing one end secured to one side of the main
line and its other end to the tail block, a
third block through which the shifting line
passes between the other two blocks and a
snubbing line secured to the said third block. 105

3. A means for laterally shifting the tail
end of a cableway having a looped main line
and a tail block, comprising a shifting block
secured in the direction of the new location,
a shifting line passing through the shifting
block and means for securing one end of the
shifting line to one side of the main line and
its other end to the tail block, and a snub-
bing line secured to yieldingly hold the tail
block against the action of the shifting line. 115

4. A means for laterally shifting the tail
end of a cableway comprising a shifting line
connected with the tail end of the cableway, 125
a block for said line located at the new loca-
tion, and means for operating said shifting
line from a cableway line.

5. A means for laterally shifting the tail
end of a cableway comprising a block se- 130

cured to the new tail support, a shifting line passing through said block, a clamp for securing one end of the shifting line to an operating line of the cableway, the other end 5 of the shifting line being connected with the tail end of the cableway, and a snubbing line carrying a block mounted upon that end of the shifting line which is connected with the tail end of the cableway.

10 6. The method of laterally shifting the tail end of a cableway which consists in applying power communicated through the cableway main line to laterally shift the cableway and to support it while shifting from 15 one tail support to another.

7. The method of laterally shifting the tail end of a cableway between stationary tail supports which consists in communicating power from the cableway to the new tail 20 support to laterally swing the cableway to the new position while yieldingly restraining such movement from the old location.

8. A means for shifting an end of a cableway between two laterally separated sup-

ports comprising a shifting line having one 25 end connected to serve as a suspending support for the cableway end and its other end connected with an operating line of the cableway, a guide for the shifting line positioned to swing the cable to the new location, 30 and a snubbing line connected to the cable to yieldingly hold it against said lateral transfer.

9. A means for laterally shifting an end of a cableway comprising a shifting line 35 having one end connected with the cableway to form a suspending support therefor and its other end connected with an operating line of the cableway, two guides for said line located respectively at the new and at 40 the old locations, and means whereby the latter guide may be controlled to permit its gradual shifting over into alignment with the cable in its new location.

Sign'd at Seattle, King County, Washington this 15th day of April, 1921.

GERALD FRINK.
